FIG. 4.

UNITED STATES PATENT OFFICE.

ANTONI RUDNICKI, OF CHICAGO, ILLINOIS.

ROCKING-CHAIR.

1,399,155.

Specification of Letters Patent.

Patented Dec. 6, 1921.

Application filed August 3, 1920. Serial No. 400,985.

To all whom it may concern:

Be it known that I, ANTONI RUDNICKI, a citizen of Poland, residing at Chicago, in the county of Cook and State of Illinois, 5 have invented certain new and useful Improvements in Rocking-Chairs, of which the following is a specification.

This invention relates to certain new and useful improvements in rocking chairs and 10 has for its primary object to provide a rocking chair embodying a bellows attachment whereby rocking movement of the chair will create a current of air for circulation through passages in the chair frame and es- 15 caping from outlets in communication with the passages and directed toward the occupant of the chair.

A further object of the invention aims to provide an air blowing attachment for rock- 20 ing chairs wherein bellows elements are at- tached to the chair and supporting frame with spring devices for causing the chair to assume a normally central position relative to its support, a further object con- 25 templating an adjustable foot rest for the occupant of the chair, the foot rest having guide means slidably associated with the chair beneath the seat portion thereof.

With the above general objects in view 30 and others that will appear as the nature of the invention is better understood, the same consists in the novel form, combination and arrangement of parts hereinafter more fully described, shown in the accompanying draw- 35 ings and claimed.

In the drawings, wherein like reference characters indicate corresponding parts throughout the several views,

Figure 1 is a side elevational view of a 40 rocking chair constructed in accordance with the present invention, the adjustable foot rest being shown projected in dotted line position.

Fig. 2 is a top plan view of the same 45 showing the air exit openings in the chair bottom and side arms,

Fig. 3 is a horizontal sectional view taken on line III—III of Fig. 1 showing the bellows attachments and centering springs for 50 the rocking chair,

Fig. 4 is a front elevational view of the chair, partially broken away, and

Fig. 5 is a detail sectional view on line 55 V—V of Fig. 4 showing the bellows construction.

Referring more in detail to the accom-

panying drawings, there is illustrated a rocking chair mounted upon a base frame and having devices associated therewith for creating a current of air during the rocking movement of the chair with air passages in the chair frame having exit openings directed toward the seat portion of the chair, the base frame including a pair of side bars 1 mounted upon end feet 2, preferably of 60 cushioning material and having the upper faces thereof grooved or channeled as at 3 to provide guideways for the rockers of a chair. Transverse bars 4 connect the side bars 1 and hold the same in spaced relations as 70 clearly shown in Figs. 3 and 4.

The rocking chair comprises forward and rearward corner posts 5 and 6 of any preferred design connected by the arm rests 7 adjacent their upper ends and connected at 75 their lower ends to the rocker feet 8, the lower faces of which are provided with cushioned treads 9 with the rockers and the cushion treads extending into the upper grooved faces 3 of the frame bars 1 clearly 80 shown in Figs. 1, 2, and 4. A rectangular seat board 10 is attached to the corner posts 5 and 6 while a back support 11 of any desired curvature extends between the rear posts 6 as shown in Fig. 4. 85

Means is associated with the rocking chair and supporting frame for creating a current of air through the rocking chair and embodies the mounting of a platform 12 upon feet 13 supported on transverse bars 4 as 90 shown in Figs. 1 and 4 and is held immovable relative to the base frame. A bellows 14 of the type clearly shown in Fig. 5 extends between the platform 12 and the seat bottom 10 at the front and rear edges thereof. Each bellows 14 has a controlling inlet valve 15 at the lower end thereof overlying a registering opening 12' in the platform 12 while the upper end of the bellows is provided with an unrestricted opening 14' regis- 95 tering with an opening 10' in the bottom face of the chair bottom 10, the chair bottom having an inner chamber 16 providing a circulating air space with outlet openings 17 in the upper face of the chair bottom 10 and 105 arranged at desired points as shown in Fig. 2. The rear posts 6 of the chair are provided with air passages 18 in communication with the air passage 16 in the chair bottom 10 with exit openings 18' for the passages 18 adjacent the upper ends of the posts 6. To 110 provide for a normal central positioning of

the rocking chair upon the base frame bars 1, there is provided a plurality of coil springs 19 centrally connected to the ring 20 at the underside of the chair bottom 10 and radiating therefrom and anchored at their ends as at 21 to the corners of the platform 12.

An adjustable foot rest embodies a foot board 22 carried by arms 23, slideable in guides 24 carried by the opposite sides of the 10 chair frame as shown in Fig. 4.

An occupant within the chair resting upon the seat 10 and back 11 may have his feet supported on the foot board 22 of the extension frame. Rocking movement of the chair 15 is assisted by the springs 19 connected to the chair bottom and the stationary platform 12, such rocking movement communicating reciprocating motion to the bellows 14, alternately operating to draw air through the 20 openings 12' in the platform 12 by way of the valve 15 and force the same through the opening 10' in the seat to the air compartment 16, the current of air circulating therefrom and escaping through the exit openings 25 17 in the chair bottom and through the exit openings 18' in the rear side posts of the chair. The rockers 8 of the chair being mounted upon cushioned feet 9 and guided

in the channels 3 of the bars 1, an easy shock absorbing motion is provided for the chair, 30 the alternately operating bellows providing a constant current of air circulating through the chair frame and escaping through openings in the manner described.

While there is herein shown and described 35 the preferred embodiment of the present invention, it is nevertheless to be understood that minor changes may be made therein without departing from the spirit and scope of the invention as claimed. 40

What is claimed as new is:—

The combination with a rocking chair of a mounting base therefor, a platform supported on the mounting base including forward and rear upright standards and a rectangular plate upon said standards, an air bellows rigidly connected to the forward and rear ends of said plate in engagement with the chair bottom and spring tension means anchored to the four corners of said plate 50 and the underneath center portion of said chair bottom for normally maintaining the chair in a level position.

In testimony whereof I affix my signature.

ANTONI RUDNICKI.
